UNITED STATES PATENT OFFICE.

FRANK H. BOGDA, OF HORICON, WISCONSIN.

STANCHION-ALINEMENT DEVICE.

1,312,677.

Specification of Letters Patent. Patented Aug. 12, 1919.

Application filed June 1, 1918. Serial No. 237,690.

To all whom it may concern:

Be it known that I, FRANK H. BOGDA, a citizen of the United States, and resident of Horicon, in the county of Dodge and State of Wisconsin, have invented new and useful Improvements in Stanchion-Alinement Devices, of which the following is a description, reference being had to the accompanying drawings, which are a part of this specification.

The invention relates to stanchion alinement devices for adjusting the stanchion backwardly or forwardly with respect to the stall frame so that the animal may be properly positioned with respect to the gutter.

Heretofore in connection with devices of this kind to effect the adjustment it has been necessary to loosen bolts or screws on the alinement devices or to take apart these devices to accomplish the adjustment and it is the object of this invention to do away with this difficulty and provide an alinement device in which the parts may be moved to adjusted position and there secured without having to loosen up or take out and replace bolts or screws and without having to use any tools.

A further object of the invention is to provide a quickly detachable interlocking connection for the adjustable anchoring device for the lower end of the stanchion and to provide a top aliner of such a construction as to permit of adjustment when one of the lower anchoring devices has been detached from the adjacent stall upright.

With these and other objects in view the invention consists in the several features hereinafter set forth and more particularly defined by claims at the conclusion hereof.

In the drawings:

Figure 1 is an elevation view of a stall and stanchion equipped with the alinement device embodying the invention, parts being broken away;

Fig. 2 is a plan view of one of the lower stanchion alinement devices;

Fig. 3 is a section taken on the line 3—3 of Fig. 2;

Fig. 4 is a vertical sectional view taken through the top alinement device;

Fig. 5 is a section taken on the line 5—5 of Fig. 4.

In the drawings, the numeral 6 designates the curb, 7 and 8 the stall frame members, 9

partitions secured to said frame members and 10 the stanchion secured at its upper portion to the frame members 8 by the top aliner hereinafter described and secured at its lower portion to the lower portion of the 60 frame members 8 by the bottom alinement device hereinafter described.

The bottom alinement device consists of a chain 12 medially connected to a fitting 13 on the lower end of the stanchion and adjustably connected to the lower portion of the frames 8 by hooked members 14 having detachable interlocking connections with plates 15 secured to the uprights by clips 15'.

The hooked members 14 are secured to the 70 ends of the chain 12 by bolts 16 and the hooked ends 17 are T-shaped. The plate 15 is provided with apertures 18 and a central aperture 19. The apertures 18 have elongated slots 20 communicating therewith and with each other while the aperture 19 has an elongated slot 21 communicating with it. The hooked member can be hooked into any of the apertures by passing the T-shaped head through the slots 20 or 21 but said 80 head cannot be shifted from one aperture 18 to another. With this construction two spaced adjustments may be had on either side of the central aperture 19 or a central adjustment may be had and the T-shaped 85 head will be held in interlocking engagement with the plate 15 but may be quickly removed by drawing the chain toward the plate, moving the T-shaped head until it is in line with the slot adjacent the aperture and then the head may be drawn up to disconnect the chain from the plate.

The top aliner consists of a member 22 having a hollow interior portion 22', a longitudinally extending rib 23 depending from the top 24, a longitudinally extending slot 25 in the bottom 26, and spaced curved recesses 27 on opposite sides of the slot 25 with recesses 28 adjacent thereto. It is obvious that instead of using a single rib that short 100 ribs disposed above each of the recesses 27 may be used. This member may be secured to the stall frame in any suitable manner and in the present instance I have shown said member provided with coupling extensions 29 which with clips 30 and bolts 31 secure it to the upper ends of the stall frame members 8. The aliner further consists of a swivel bolt 32 which has a shank portion 33 provided with an aperture 33' to receive a 110

bolt to connect it to the upper portion of the stanchion, a head 34 adapted to be seated in any one of the recesses 28 to form a swivel connection and an extension 35.

5 The extension 35 prevents the bolt 32 from being moved along the aliner from one position of adjustment to the other as said extension on being moved upwardly abuts against the rib 23 but by turning said member until the extension 35 is in line with the rib and then swinging said member to one side or the other transversely of the slot 25 so that the extension is out of engagement with said rib the bolt 32 may be moved along the slot from one set of recesses 27 to another and by swinging it back over the rib 23 and turning it so that the extension 35 is disposed transversely of the rib 23 the member will be secured in its adjusted position and its head 34 will be free to turn in the recess 28, the shank passing down through the opening formed by the recesses 27 adjacent the recess 28. In assembling the device the bolt 32 is passed into the hollow interior portion 22' through either of the openings 36 in the sides 27 and the shank is then moved to a position within the slot 25.

With this construction when one of the ends of the chain has been released from interlocking engagement with the adjacent plate 15, the stanchion together with the bolt 32 is turned and then tipped or swung toward one side as previously explained in connection with the adjustment of said bolt 32 in the member 22 and the bolt 32 with the stanchion is moved forwardly, backwardly or to central position with respect to the stall frame members as desired until it has been brought into register with the desired opening formed by the recesses 27 and then the stanchion is swung back and turned thereby securing the bolt 32 in swiveled engagement with the member 22 as previously described and it will be noted that in making this adjustment it is not necessary to take the top aliner apart or remove any bolts or screws from either of the alignment devices so that the adjustment may be quickly made and without the use of any tools.

I am aware that the specific embodiment of the invention herein shown and described is capable of modification and change and I therefore desire it to be understood that such changes as come within the scope of the

appended claims I deem to be within the spirit of my invention.

What I claim as my invention is:

1. The combination, with a stanchion and stall uprights, of plates secured to the lower ends of said uprights and provided with spaced apart slots, members having hooked T-shaped ends insertible in any one of said slots and thereby held in interlocking engagement with said plates, and means for connecting said members to the lower portion of the stanchion. 65

2. The combination, with a stanchion and stall uprights, of plates secured to the lower ends of said uprights and provided with spaced apart slots, members having hooked ends insertible in any one of said slots and movable a partial revolution into locking engagement with said plates, and means connecting said members to the lower portion of the stanchion. 70

3. The combination, with a stanchion and stall frame uprights, of plates secured to the lower ends of said uprights and provided with spaced apertures, a chain medially connected to the lower end of the stanchion, and hooks secured to the ends of the chain and insertible in any one of said apertures in said plates to secure the lower end of the stanchion in adjusted position, 80 and means carried by said hooks and integral therewith for normally preventing the removal of the hooks from the plates without moving the hooks from their normal operative position. 85

4. The combination, with a stanchion and stall frame, of a bottom aliner comprising a tensioning member secured to the lower end of the stanchion and having dis- 95 connectible connections with the lower ends of the stall frame, a top aliner consisting of a member provided with a plurality of spaced apart recesses in communication with each other, a swivel bolt secured to the upper portion of the stanchion having a 100 head adapted to be seated in any one of said recesses, means normally preventing the removal of the bolt from one recess to another but permitting removal of the bolt and transference to another recess when the tensioning member has been disconnected from one of the stall uprights. 105

In testimony whereof, I affix my signature.

FRANK H. BOGDA.
